(57) **CLAIM**

The ornamental design for a multi-functional thermometer, as shown and described.

DESCRIPTION

FIG. 1 is a first perspective view of a multi-functional thermometer showing my new design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a third perspective view showing the multi-functional thermometer in a use state.

The broken lines in the drawings illustrate portions of the multi-functional thermometer which form no part of the claimed design.

The diagonal lines in the drawings represent reflective surfaces.
